Primary Examiner—Charles A. Rademaker(74) *Attorney, Agent, or Firm*—John A. Doninger(57) **CLAIM**

The ornamental design for a serving bowl, as shown and described.

DESCRIPTION

FIG. 1 is a top, right side and front perspective view of a serving bowl showing the new design;

FIG. 2 is a front elevation view thereof, the rear elevation view being identical thereto;

FIG. 3 is a right side elevation view thereof, the left elevation view being identical thereto;

FIG. 4 is a top plan view thereof;

FIG. 5 is a bottom plan view thereof;

FIG. 6 is a top, right side and front perspective view of a second embodiment showing the new design;

FIG. 7 is a front elevation view thereof, the rear elevation view being identical thereto;

FIG. 8 is a right elevation view thereof, the left elevation view being identical thereto;

FIG. 9 is a top, right side and front perspective view of a third embodiment showing the new design;

FIG. 10 is a front elevation view thereof, the rear elevation view being identical thereto; and,

FIG. 11 is a right side elevation view thereof, the left elevation view being identical thereto.
